UNITED STATES PATENT OFFICE.

OSCEOLA DE LOS BRAINARD, OF GREAT FALLS, MONTANA.

AUTOMATIC GAGE.

1,389,432.

Specification of Letters Patent. Patented Aug. 30, 1921.

Application filed June 4, 1920. Serial No. 386,657.

To all whom it may concern:

Be it known that I, OSCEOLA DE LOS BRAINARD, a citizen of the United States, and a resident of Great Falls, in the county 5 of Cascade and State of Montana, have invented a new and Improved Automatic Gage, of which the following is a full, clear, and exact description.

This invention relates to improvements in 10 automatic gages, and more particularly to gages designed to be used on linotype saws, an object of the invention being to eliminate as far as possible the necessity of hand-work in spacing matter to fit ruled book 15 headings and the like.

A further object is to provide a gage of 20 the character stated which can be used in connection with any ordinary type of linotype saw and which will operate to hold the slugs in position for cutting off the 25 ends of the slugs so that the matter set up will be in exact conformity in size and in spaced relation to the headings desired without the necessity of measuring with a rule 30 the exact distances and proportions in picas and points.

A further object is to provide improvements of the character stated which result 35 in an economy of time and labor and give 40 more accurate results than possible under ordinary methods.

With these and other objects in view the invention consists in certain novel features of construction, and combinations and arrangements of parts as will be more fully 45 hereinafter described and pointed out in the claims.

In the accompanying drawings—

Figure 1 is a view in front elevation 40 illustrating my improvements in connection with a well-known type of saw trimmer in general use.

Fig. 2 is a broken plan view.

Fig. 3 is a view in longitudinal section 45 on the line 3—3 of Fig. 2.

Fig. 4 is a view in transverse section on the line 4—4 of Fig. 2.

Fig. 5 is a fragmentary plan view showing 50 the final position of the gage for holding the slugs.

Fig. 6 is a view in transverse section on the line 6—6 of Fig. 2.

Fig. 7 is a fragmentary view in section on the line 7—7 of Fig. 5.

55 1 represents the supporting table of a saw trimmer machine on which a top plate

2 is secured by means of screws 3 or other approved attaching means. On the plate 2 I provide a pair of standards 4 and 5 in which the reduced ends 6 of an adjusting 60 shaft 7 have rotary mounting, the standards operating to hold the shaft against longitudinal movement. A finger hold or hand wheel 7' is secured on one end 6 to facilitate the turning of the shaft. 65

This shaft 7 is in reality an adjusting screw and is provided at one end with screw threads 8 and at its other end with screw threads 9. These screw threads are of different pitch, the threads 8 being of exactly 70 twice the pitch of the threads 9, or, in other words, there are twice as many threads 9 to the inch as there are threads 8 for a purpose which will hereinafter appear.

The threaded portions 8 and 9 project 75 through internally screw threaded burs or riders 10 and 11 respectively. These burs or riders have dove tailed grooves 12 in their lower faces receiving dove tailed tenons 13 on blocks 14 and 15 respectively. The burs 80 and the blocks are coupled against accidental movement by means of removable pins 16 which project through the burs and into the blocks as shown clearly in Fig. 4, so that the blocks are moved by the turning 85 movement of the screws.

These blocks 14 and 15 are provided with laterally projecting arms 17 and 18 respectively and said arms 17 and 18 are made with aligned circular openings 19 to receive 90 and support a rod 20, the latter having at its forward end a T-head 21. A dog 22 is pivotally connected to the arm 17 as shown at 23, and is pressed downwardly against the rod 20 by means of a spring 24. 95

The rod 20 at one end is made with a flattened portion 25 which, at its point of juncture with the circular or cylindrical portion of the rod, forms a shoulder 26 for a purpose which will hereinafter appear. 100

A stationary spring pressed gage plate 27 is supported on a rod 28 mounted in brackets 29 on the plate 2 and at its free edge is downwardly pressed by means of a spring 30 on one end of the rod and a finger hold 31 105 is provided on the extreme end of the rod to permit the gage plate 27 to be elevated or adjusted as may be desired.

A spool 32 is mounted in a stationary bracket support 33 on plate 2 and is operated by a knob or finger hold 34 at one end. 110 This spool 32 is adapted to support a copy

strip 35 which we will assume contains the column headings desired to be set up, and this copy strip 35 is fed under the gage plate 27.

- 5 A second and movable gage plate 36 is mounted in upright 37 on a platform 38 which constitutes an integral part of the block 14. This gage plate 36 is operatively connected to a supporting rod 37', the latter provided with a spring 39 to press the free edge of the gage plate downwardly and a finger hold or knob 40 is provided on the rod to adjust or move the gage plate vertically. The copy strip 35 is positioned under 10 this gage plate 36 and the inner or adjacent edges of the gage plates 27 and 36 are adapted to register with the sides of the column to be set up as will be explained.

I have illustrated at 41 a rotary saw such 20 as commonly employed, but have not attempted to illustrate the particular manner of operating the saw or moving the same toward the plate 2 or the latter toward the saw as may be desired, but it is to be understood that these parts operate in the ordinary way with machines of the same general type in use.

I have illustrated in Fig. 1 in side elevation an ordinary form of saw trimmer for 30 the purpose of locating my improved mechanism thereon, but as the details of this trimmer form no part of my invention, it is not necessary to describe the same in detail.

42 represents linotype slugs which are 35 adapted to be placed beside a guide plate 43 at one edge of the plate 2 and supported upon an extension 44 for the cutting operation, as will now be described.

The copy strip 35 is projected under the 40 gage plate 27 and also under the gage plate 36; the rig being in normal position, the gage plate 36 and bur 10 and projecting arm 17 appear one inch farther to the right than shown in Fig. 2, and line up against 45 and with the inside edge of gage plate 27; bur 11 and projecting arm 18 being one-half inch farther to the right than shown in Fig. 2, bringing bur 11 up flush against the inside edge of a standard 5; T-head 21 resting against projecting arm 18 (as shown in Fig. 2) would then be one-half inch farther to the right, also, than is shown in Fig. 2. Now, by drawing T-head 21 to right until 50 dog 22 engages flattened portion 25 of rod 20 and rod 20 is held inwardly until the dog 22 engages the left shoulder 26 on the rod 20, the right hand face of T-head 21 will register flush with saw trimmer line. Let us understand that inside edge of gage plate 55 36 is now clamped in register with the left hand side of column on copy strip 35. Tension gage plate 27 is released and shaft 7 is now turned to move the gage plate 36 with the copy strip 35 to the left until the right 60 hand side vertical ruling of columns on copy

strip 35 appears in register with inside edge of gage plate 27 as is shown in Fig. 2. At this juncture gage plate 36, bur 10 and projecting arm 19, and bur 11 and projecting arm 18, will be exactly in position shown 70 in Fig. 2.

In turning the shaft 7 the burs or riders 10 and 11 are caused to move longitudinally, but due to the different pitch and number of teeth on the sections 8 and 9, the bur 75 10 will be moved exactly twice the distance of the movement of the bur 11, as shown in Fig. 2. In placing the slugs 42 to be sawed, the dog 22 is held in an elevated position; slugs 42 placed against T-head and pressed 80 inwardly, causing a longitudinal movement of that portion of rod 20 bearing shoulder 26 to pass free to left under dog 22 until T-head is stopped in contact with the projecting arm 18, as shown in Fig. 2, leaving 85 the slugs projected beyond the edge of plate 2 to be sawed exactly one-half the distance from the center of the slugs to the saw trimmer line of the distance of the movement imparted to the bur 10 in order to register the right-hand side of the column on copy strip 35 with gage plate 27. The 90 slugs are then in the position for cutting off the metal at one end thereof, and this operation is carried out by means of the saw 41. 95 The slugs are then reversed in position and the T-head 21 drawn outwardly until the dog 22 engages the flat portion 25 of the rod 20 when the rod 20 is moved inwardly until the dog 22 engages the shoulder 26 on 100 the rod 20, and when in this position, the T-head 21 will hold the slugs projected a distance exactly equal to the distance they were projected before so that the opposite ends of the slugs can be cut off and the lengths of 105 the slugs left will be in exact accordance with the width of the column on the copy strip.

It is therefore apparent that with my invention it is not necessary to calculate in 110 picas and points the particular measurements needed for cutting off the ends of the slug as the movement of the plate 36 will be equal to the complete length of slug to be cut off, but this length is equally proportioned between the ends of the slugs by reason of the operation above described.

When it is desired to adjust the parts, the pins 16 can be removed and the blocks 14 and 15 moved transversely of the plate to 115 disconnect them from the burs so that the burs can be quickly moved by turning the screw and the blocks replaced in operative position thereto at any desired starting point of the operation.

120 Various slight changes might be made in the general form and arrangement of parts described without departing from the invention, and hence I do not limit myself to the precise details set forth, but consider 125 130

myself at liberty to make such changes and alterations as fairly fall within the spirit and scope of the appended claims.

I claim:

5. 1. A device of the character described, comprising a copy support, means registering with the column lines of a copy on the support, a saw, means for projecting slugs beyond the support for engagement with the saw, and means compelling the movement of the slugs a distance from their center to saw line exactly half the distance of movement imparted to the column registering means. 70
10. 2. A device of the character described, comprising a copy support, means registering with the column lines of a copy on the support, a saw, means for projecting slugs beyond the support for engagement with the saw, means compelling the movement of the slugs a distance from their center to saw line exactly half the distance of movement imparted to the column registering means, and other means for projecting the slugs a 75 distance exactly equal to the first-mentioned distance of movement. 80
15. 3. A device of the character described, comprising a copy support, means registering with the column lines of a copy on the support, a saw, means for projecting slugs beyond the support for engagement with the saw, means compelling the movement of the slugs a distance from their center to saw line exactly half the distance of movement imparted to the column registering means, and other means for projecting the slugs a 85 distance exactly equal to the first-mentioned distance of movement, both of said last-mentioned means automatically controlled 90 by the position of the copy registering means. 95
20. 4. A device of the character described, comprising a support, a saw operatively connected to the support, a copy holder on the support, a stationary gage plate above the copy holder, a movable gage plate above the copy holder, said gage plates adapted to register with the sides of columns of a copy on the support, means for moving one of 100 said gage plates and simultaneously moving a slug guide to project slugs for cutting a distance from their center to saw line exactly equal to half the movement of said movable gage plate, and other means 105 for guiding the position of the slugs for cutting the other ends of the slugs a distance equal to the first-mentioned cutting distance. 110
25. 5. A gage of the character described, comprising a shaft having threads at its respective ends, the threads at one end being of twice the pitch of the threads at the other end, burs mounted on the respective threaded ends of the shaft, a rod supported by the burs, a slug engaging head on the rod, a shoulder on said rod, a spring pressed dog carried by one of said burs and adapted to engage the shoulder on the rod, a sta- 115 120
30. 6. A gage of the character described, comprising a shaft having threads at its respective ends, the threads at one end being of twice the pitch of the threads at the other end, burs mounted on the respective threaded ends of the shaft, a rod supported by the burs, a slug engaging head on the rod, a shoulder on said rod, and a spring 125 130
35. 7. A gage of the character described, comprising a shaft having threads at its respective ends, the threads at one end being of twice the pitch of the threads at the other end, burs mounted on the respective threaded ends of the shaft, a rod supported by the burs, a slug engaging head on the rod, movable coupling means connecting one of said burs to the rod, a stationary gage plate, and a movable gage plate operatively connected to one of the burs and adapted to register with the column of a copy strip when moved by its bur. 90
40. 8. A gage of the character described, comprising a shaft having threads at its respective ends, the threads at one end being of twice the pitch of the threads at the other end, burs mounted on the respective threaded ends of the shaft, a rod supported by the burs, a slug engaging head on the rod, a shoulder on said rod, a spring pressed dog carried by one of said burs and adapted to engage the shoulder on the rod, a stationary gage plate, and a movable gage plate operatively connected to one of the burs and adapted to register with the column of a copy strip when moved by its bur. 100
45. 9. A gage of the character described, comprising a shaft having threads at its respective ends, the threads at one end being of twice the pitch of the threads at the other end, burs mounted on the respective threaded ends of the shaft, a rod supported by the burs, a slug engaging head on the rod, movable coupling means connecting one of said burs to the rod, a stationary gage plate, a movable gage plate operatively connected to one of the burs and 110 adapted to register with the column of a copy strip when moved by its bur, and a stationary copy strip roll from which the copy strip is adapted to be fed under said gage plates. 115
50. 10. A gage of the character described, comprising a shaft having threads at its respective ends, the threads at one end being of twice the pitch of the threads at the other end, burs mounted on the respective threaded ends of the shaft, a rod supported by the burs, a slug engaging head on the rod, a shoulder on said rod, a spring pressed dog carried by one of said burs and adapted to engage the shoulder on the rod, a sta- 120 125
55. 11. A gage of the character described, comprising a shaft having threads at its respective ends, the threads at one end being of twice the pitch of the threads at the other end, burs mounted on the respective threaded ends of the shaft, a rod supported by the burs, a slug engaging head on the rod, a shoulder on said rod, and a spring 130

tionary gage plate, a movable gage plate operatively connected to one of the burs and adapted to register with the column of a copy strip when moved by its bur, and a 5 stationary copy strip roll from which the copy strip is adapted to be fed under said gage plates.

11. In a device of the character described, the combination with a supporting plate, 10 and a saw adjacent thereto, of a shaft having rotary mounting on the plate and having threads at its ends, the threads at one end of the shaft being exactly twice the pitch of the threads at the other end of the 15 shaft, burs mounted on the threaded ends of the shaft, blocks coupled to the burs,

arms on the blocks having alined openings therein, a rod mounted in the openings, a head on the rod adapted to receive the ends of linotype slugs, said rod having a flattened portion at one end and a shoulder at the end of the flattened portion, a spring 20 pressed dog carried by one of said arms and adapted to engage the rod, and when said rod is moved in one direction engage 25 the shoulder of the rod and limit the movement of the rod in one direction, copy supporting means on the plate, and a gage plate operatively connected to one of the burs and registering with the copy strip on 30 the supporting plate.

OSCEOLA DE LOS BRAINARD.
